UNITED STATES PATENT OFFICE.

WILSON F. WILEY AND ADOLPH REINBERG, OF SALT LAKE CITY, UTAH.

DESIGN FOR A TIRE-TREAD.

59,312.

Specification for Design.

Patented Oct. 4, 1921.

Application filed January 5, 1920. Serial No. 349,617. Term of patent 7 years.

To all whom it may concern:

Be it known that we, WILSON F. WILEY and ADOLPH REINBERG, citizens of the United States, residing at Salt Lake City, county of Salt Lake, State of Utah, have invented a new, original, and ornamental Design for Tire-Treads, of which the following is a specification, reference being had to the accompanying drawing, forming part thereof.

The figure is a perspective view of a portion of a tire, showing our new design.

We claim:

The ornamental design for a tire tread, as shown.

WILSON F. WILEY.
ADOLPH REINBERG.
